UNITED STATES PATENT OFFICE.

EDWIN N. CHANDLER, OF BRAINTREE, MASSACHUSETTS.

INSOLE.

1,311,154.

Specification of Letters Patent. Patented July 29, 1919.

Application filed March 28, 1916. Serial No. 87,334.

To all whom it may concern:

Be it known that I, EDWIN N. CHANDLER, a citizen of the United States, and resident of Braintree, county of Norfolk, and State 5 of Massachusetts, have invented an Improvement in Insoles, of which the following description, in connection with the accompanying drawings, is a specification, like letters on the drawings representing like parts.

10 My present invention is an improved insole for use in the manufacture of welt boots and shoes. In preparing the insole for a welt shoe, it is necessary to form a sewing rib around the forepart and shank 15 and my present invention relates particularly to this feature, enabling an improved welt insole to be produced from very thin stock, as well as from inexpensive leather. The use of thin and inexpensive leather in 20 insoles is of great importance, constituting a material saving in the cost of a shoe, but heretofore it has been found very difficult in utilizing such material for insoles, the sewing rib formed thereon being apt to tear out, 25 particularly around the toe. My invention contemplates the provision of a sewing rib constituting a plurality of members, preferably united by adhesives into a composite rib. I prepare my improved welt insole by 30 forming two parallel lips or flaps parallel with the marginal portion, splitting the edge of the insole and turning up one lip, then channelling the insole and turning up a second lip or flap parallel with the first, 35 and then interposing a reinforcing element between the lip and flap cut from the insole, thus constituting a composite sewing rib of at least three members, the intermediate reinforcing element being of any suitable ma- 40 terial, such as a strip of tape, thin leather, or a cord, and preferably these three members are united by any suitable adhesive into a solid and rigid sewing rib. The adhesive may be applied in any manner, for example, 45 the reinforcing element may be coated with the adhesive as the same is fed into position, and the union of three members may be completed by pressure, or by heat and pressure, or otherwise, such as by staples, 50 stitches or the like. An insole thus prepared presents a sewing rib, (even with the lip and flap cut therefrom being extremely thin) of great strength, owing to the continuous reinforcing element between the two other 55 members. Especially this strength is im- parted around the toe, and the lip and flap

being of thin substance will fold easily, substantially without wrinkles, over the intermediate reinforcing element, around curved portions and sharp toes.

60

While it is old in this art to cut both a lip and flap in an insole, to form the sewing rib thereby, it is believed to be a distinct novelty to use a lip and flap with an intermediate reinforcing element, and I wish to claim the 65 same broadly. This construction of an intermediate and preferably continuous reinforcing member results in many advantages, such as enabling thin stock to be used for insoles, a very thin lip and flap cut therefrom, 70 even folding of the lip and flap upon the intermediate reinforcing element, eliminating wrinkles around the toe and other curved portions, and furthermore enabling cheap and hard stock to be employed, which ordi- 75 narily would not enable a channel flap or rib to be cut and successfully used.

In the process of forming my improved insole, I prefer to use adhesive to unite the three members constituting the sewing rib, 80 and preferably apply said adhesive by coating the intermediate reinforcing element.

Referring to the drawings illustrating a preferred embodiment of my invention:

Figure 1 is a plan view of my prepared 85 insole showing the composite rib uppermost;

Fig. 2 is a plan view of the insole partially completed;

Fig. 3 is a cross-sectional view slightly enlarged on the line 3-3 of Fig. 1 showing 90 a corded type of reinforcing element; and

Fig. 4 is a similar cross-sectional view to Fig. 3, showing a strip type of reinforcing element.

The insole 1 is usually formed with a con- 95 tour substantially as desired for a particular style and size of shoe, and the marginal portion is then split and the resulting feather 2 formed, and a lip 3 cut therefrom is turned upwardly, entirely around the mar- 100 ginal portion of the forepart and shank on the insole.

Parallel with the rib 3 and on the inner side thereof a channel 4 is cut, and the resulting flap 5 turned upwardly constituting 105 a second member preferably of the same height and equal in extent around forepart and shank with the lip 3. Between this lip and flap is then applied a reinforcing element 6, which, as shown in Figs. 1, 2 and 110 3, is a cord, constituting the intermediate member of the composite sewing rib. As

shown in Fig. 4, this intermediate member 7 may be in strip form, and of textile material, or of thin scrap leather. I prefer to unite the three members constituting the composite rib by means of an adhesive, rubber cement being well suited to this purpose, forming a rigid rib of great strength, even though the three elements composing it are each extremely thin. The three members 10 may be simply held in shape by the relatively heavy molding pressure applied thereto, if desired, or by thin metallic staples, or a few stitches, being more permanently united by the inseam stitching in 15 the subsequent welt sewing operation, some of such inseam stitching usually passing through all three members in the rib.

My prepared insole after the welt sewing operation, enables the lip 3, flap 5 and 20 intermediate reinforcing member to be readily trimmed by the inseam trimming cutters. The intermediate reinforcing element will enable the inseam stitching to be "set" with considerable tension, without danger of 25 tearing through the composite sewing rib, especially around the toe, where such damages are especially apt to occur. The entire insole may be quickly and economically manufactured, of the less expensive leather 30 stock, as well as of very thin material.

My invention is further described and defined in the form of claims as follows:

1. A welt insole for boots and shoes, comprising a leather blank having a composite sewing rib formed around the marginal portion of the forepart and shank of the blank, consisting in a lip and a flap cut from said blanks parallel with each other and each turned upwardly and backwardly toward the other, being united by an intermediate 40 reinforcing element between the lip and flap to constitute the composite sewing rib. 35

2. A welt insole for boots and shoes, comprising a leather blank having a composite sewing rib formed around the marginal portion of the forepart and shank of the blank, consisting in a lip and a flap cut from said blanks parallel with each other and each turned upwardly and backwardly toward the other, a continuous reinforcing element 45 between said lip and flap and means to unite the lip and flap and reinforcing together into a substantially solid sewing rib. 50

In testimony whereof, I have signed my name to this specification, in the presence 55 of two subscribing witnesses.

EDWIN N. CHANDLER.
